UNITED STATES PATENT OFFICE

ALBERT J. JAMESON, OF WORCESTER, MASSACHUSETTS

QUICK ACTING VISE

Application filed October 20, 1930. Serial No. 489,775.

The principal objects of this invention are to provide a quick-acting vise, principally for use by wood workers, by which the motion can be imparted to the movable jaw in a very quick way and it can be disconnected readily so as to permit it to be pulled out to free the work; to provide positive means for holding the jaws closed and to provide an improved mechanism for operating the vise.

Other objects and advantages of the invention will appear hereinafter.

Reference is to be had to the accompanying drawings in which

Fig. 1 is a side view of a vise constructed in accordance with this invention;

Fig. 2 is an end view as indicated by the arrow 2 in Fig. 1;

Fig. 3 is an opposite end view as indicated by the arrow 3 in Fig. 1;

Fig. 4 is a sectional view on the line 4—4 of Fig. 1;

Fig. 5 is a plan of the vise in the position shown in Fig. 1 and

Fig. 6 is a plan of the operating handle and connected parts showing a portion of the frame in section.

The fixed jaw 10 of the vise is made preferably as an integral part of a stationary plate 11 which is fixed through holes 12 to a stationary base or frame, not shown. On the bottom of the plate 11 is fixed by screws 13 a rack 14. In a place near the front of the plate 11 is an integral stop 15. The stationary part just described is provided with a curved ratchet bar 16 having slanting teeth thereon. On the bottom of the plate 11 are longitudinal ways 17 formed preferably in lugs cast integrally with the plate.

In the ways runs a slide 18 which at its end is provided with a jaw 19 cooperating with the jaw 10 to form the vise. This slide 18 is formed of two vertical sides separated from each other and secured together by an integral cross pin as 20 and also by a pin 21 mounted free to turn. A stop screw 22 is shown for the purpose of engaging the stop 15 to prevent the movable jaw from sliding all the way out.

On the pin 21 is freely rotatably mounted a pinion or gear 23 meshing with the rack 14 at all times. This gear is normally free and the rough adjustments of the movable members 19 of the vise are made by hand. Then the vise is tightened up by connecting this pinion positively with a movable element and turning it in the proper direction to close the vise and apply pressure to the article held between the jaws.

For the above purpose a handle 24 is pivotally mounted on the pin 21 constituting said movable element. This handle has a hand grip on the end and is provided with a spring pawl 25 pivoted thereon and adapted to engage the teeth of the rack 16. A spring 26 bearing against a pin on the handle 24 holds this pawl in proper position to hold the handle up as shown in full lines in Fig. 1 but it can be depressed by the thumb where it sticks out beyond the jaw 19 to tilt the pawl 25 up so that the pawl will be projected out beyond the teeth and the handle can be moved from any point upwardly to any desired point.

On the handle 24 is pivotally mounted a pawl 28 which carries a plate 29 extending across under the two upright parts of the slide 18 when the handle is moved up to its highest position. Otherwise this pawl is held back about its pivot by gravity and it is provided with a spring 30 as will appear. On moving the handle back upwardly with the pawl 25 out of engagement, the cross plate 29 will engage the upright walls of the slide 18 and push the pawl 28 backwardly in opposition to the spring 30 to remove the pawl 28 from the pinion and release the handle. Then, when the handle is brought down with the pawl 25 now engaging the teeth of the bar 16 the spring 30 will force the pawl 28 into the teeth of the pinion 23. Further downward movement of the handle will turn the pinion and cause it to roll along the stationary rack 14 to bring the jaw 19 up into firm contact with the piece of work held in the jaws.

The operation is as follows:

Motion is imparted to the movable jaw as stated by pressing downwardly on the

handle 24 and causing the jaw 19 to move against the fixed jaw 10 with any desired degree of pressure. When the work has been secured in this way the movable jaw is held in position by the pawl 25 engaging the ratchet bar 16. To release the work sufficient downward pressure is applied to the handle 24 so that the pawl 25 can be released from the ratchet bar 16. In other words the handle 24 is depressed a little so that the end of the pawl 25 is just about to pass downwardly over a tooth, then the opposite end of the pawl 25 is depressed by the operator and the pawl is released from the ratchet bar. The handle 24 is then raised to its highest position. This brings the cross plate 29 into the position shown in Fig. 4 and disconnects the pawl 28 from the pinion 23. When the handle is in this position, as shown in full lines in Fig. 1, the movable jaw 19 is free to be moved in and out by moving the handle 24 horizontally to whatever position is needed to fully release or receive the work.

This constitutes a vise which can be adjusted quickly by hand to engage the work and by which any desired amount of hand power can be used to force the jaws together with as much pressure as may be required.

The vise is quickly and easily released and when so released is absolutely free so that the movable jaw can be moved back and forth at will. The construction is strong and durable and not expensive to build considering the work which it has to perform.

Although I have illustrated and described only one form of the invention I am aware of the fact that modifications can be made therein by any person skilled in the art without departing from the scope of the invention as expressed in the claims.

Therefore I do not wish to be limited in this respect but what I do claim is:—

1. In a vise, the combination with a stationary jaw in vertical position and a plate on which said jaw is mounted and located horizontally, a horizontal rack on the bottom of said plate, a slide guided on the bottom of said plate and movable parallel with the direction of the rack, a second jaw mounted on said slide for cooperating with the first jaw, a pinion rotatably mounted on the slide and meshing with the rack, a handle oscillatably mounted on the slide, a pawl on the handle for engaging the teeth of the pinion, a plate carried by said handle and extending into a position to force the pawl out of the pinion teeth when the handle is moved to its limiting position and a spring for forcing the pawl into the teeth of the pinion when the pawl is free to move in that direction.

2. In a vise, the combination with a stationary jaw and a plate on which said jaw is mounted, a rack on said plate, a slide

guided on said plate and movable parallel with the direction of the rack, a second jaw mounted on said slide for cooperating with the first jaw, a pinion rotatably mounted on the slide and meshing with the rack, a handle, a pawl on the handle for engaging the teeth of the pinion, a plate carried by said handle and extending into a position to force the pawl out of the pinion teeth when the handle is moved to its limiting position and a spring for forcing the pawl into the teeth of the pinion when the pawl is free to move in that direction. 70

3. In a vise, the combination of a stationary plate having longitudinal ways on its sides underneath, a jaw on said plate, a rack at the center of said plate between the ways, a slide having outwardly extending flanges fitting in said ways by which the slide is supported, a second jaw on said slide cooperating with the first named jaw, a transverse pin supported by the slide, a pinion fixed on said pin and meshing with the rack, whereby the turning of the pinion on its axis will move the slide along the plate, a handle pivotally mounted on the pin and carried by said slide, a pawl pivotally mounted on the handle and provided with a plate extending across the slide and adapted to engage the edges of the slide when the handle is moved to one extreme position, whereby when the plate engages the walls of the slide the pawl is moved backwardly away from the pinion, and a spring connected with the pawl for normally moving the pawl against the teeth of the pinion. 80 85

In testimony whereof I have hereunto affixed my signature.

ALBERT J. JAMESON.
